CLOSURE FOR MOLDED PULP CONTAINERS

Roy D. Heymann, Woodbridge, Conn., assignor,
by mesne assignments, to Pulp Products Com-
pany, Inc., New York, N. Y., a corporation of
Delaware

Application September 28, 1934, Serial No. 745,895

3 Claims. (Cl. 229—5.5)

This invention relates generally to closures and more particularly to metal closures for sealing containers made of molded pulp.

More specifically, the invention relates to a one-piece metal cap or closure for a molded pulp bottle having a neck portion terminating in a restricted circular mouth. Such a bottle may comprise, generally speaking, a container made of molded paper pulp having a generally square base, a body portion of generally square cross-section, said body portion terminating in a truncated cone to form the neck and mouth.

A molded pulp container, so constructed, is admirably suited, when lined with a proper coating, for motor oils and has found rapid acceptance in the trade. This ready acceptance has been due largely to the fact that this bottle lends itself to the desirable end of thwarting the sales of substituted or inferior products.

In accomplishing this desirable result, the invention comprehends a one-piece metal cap for the mouth of the molded pulp bottle which is easily applied and sealed or crimped to form a leak-proof closure. At the same time, the cap, when sealed on to the bottle, although tightly squeezing the molded pulp walls of the neck, does not appreciably cut into the wall and thereby render it weaker. Rather, the cap structure provided by the invention strengthens and reinforces the neck. Still further, the cap may be removed by tearing the molded pulp neck by a simple motion of the hands. Simultaneously with tearing the bottle in this manner to produce a discharge opening, the bottle is very effectively rendered unfit for further practical use.

According to one form of the invention, the cap may comprise a cup portion designed to fit snugly within the mouth of the bottle and an annular apron extending from the cup and fitting the outside of the wall of the neck. The apron terminates in an annular flange extending at approximately right-angles from the apron before the cap is sealed on the neck, but, upon the sealing process, is rolled against the apron to serve multifold purposes, as will be more fully described hereinafter.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawing forming a part thereof, in which

Fig. 1 is a view in elevation of a bottle having the cap sealed thereon;

Fig. 2 is a view in cross-section showing the cap before sealing;

Fig. 3 is a view in cross-section showing the cap sealed on the bottle; and

Fig. 4 is a top view in part of the bottle and cap.

In the following description and in the claims, various details will be identified by specific names for convenience, but they are intended to be as generic in their application as the art will permit.

Like reference characters denote like parts in the several figures of the drawing.

Referring now to the drawing, 10 indicates the molded pulp bottle having a neck portion 11 in the form of a truncated cone. The one-piece cap 12 comprises a cup portion having a circular bottom 13 and a substantially vertical annular side wall 14. Extending from the vertical side wall 14 is a curved portion 15 adapted to fit over the rim of the mouth of the molded pulp neck as indicated at 18.

Extending downwardly from the curved portion 15 is an annular apron 16 which is in concentric spaced relation with the annular side wall 14 and spaced therefrom a distance slightly more than the thickness of the wall of the neck of the bottle. The annular apron 16 is disposed at an angle from the vertical slightly, in this particular instance, about 9°, inasmuch as there is a slight taper in the walls of the neck of the bottle. The taper in the apron facilitates positioning the cap on the neck of the bottle preparatory to sealing. The annular apron 16 terminates in an angular flange 17 which is disposed generally from the apron at an angle of, roughly, 90°.

When it is desired to seal the bottle with the cap, it is placed with the cup portion inserted in the mouth of the bottle, as shown in Fig. 2 of the drawing. A chuck, shown diagrammatically by dotted lines 19, is inserted in the cup portion. The flange 17 is crimped or rolled against the apron portion, as indicated at 21, by means of a roller or crimper, indicated diagrammatically by dotted lines 20. It will be noted that as pressure is exerted against the flange 17 it is ironed against the apron 16 and ultimately the apron 16 is crimped or rolled by continued pressure in a direction toward the center of the bottle neck. The annular side wall 14 of the cup aided by the chuck 19 forms a rigid buttress and the molded pulp wall is squeezed or pressed between the outside of the side wall 14 of

the cup portion and the inside of the apron 16, thus forming a leak-proof seal between the cap and bottle, as clearly shown in Fig. 3. The rounded edge formed by ironing the flange 17 against the apron 16 does not cut into the bottle but merely presses the molded pulp, yet the apron grips the neck, particularly at the locus of the annular ring or rib formed by the flange 17.

10 In selecting a metal for forming the cap, the proper thickness of sheet-metal must be determined because if the sheet is too heavy too much temper is imparted to the metal by the crimping or rolling action. Hence, unless the metal is of 15 proper thickness, difficulty arises in practice in crimping the cap, inasmuch as a splitting is likely to result if the metal is too heavy and, if too thin, the cap will not be sufficiently rigid. One form of cap which is suitable for an oil bottle 20 may be of bright iron plate approximately 0.007 inch in thickness. This has been found suitable for a cap having the following specifications: a cup portion measuring $\frac{1}{16}$ inch from the inside bottom of the cup to the uppermost portion of 25 the curved part 15, and an outside diameter of 1.394 inches-1.400 inches; the distance from the uppermost portion of the curved part to the flange 17 measures $\frac{1}{4}$ inch; the width of the flange 17 is approximately $\frac{3}{8}$ inch. Such a cap 30 has the proper temper for crimping, produces a rigid structure when sealed on the bottle and does not crack or split.

After the cap has been sealed to the bottle, it may be removed by simply tearing off the upper part of the neck of the bottle. Removal of 35 the cap without mutilation of the neck of the bottle is practically impossible. The tear is easily made between the ridges 22 and 23 on the neck. Thus, a discharge opening is easily made 40 for emptying the contents of the bottle and, at the same time, the bottle is so mutilated as to be useless for any further practical purposes as an oil dispenser.

It is seen from the foregoing description that 45 a very simple, cheaply manufactured closure device may be produced for a molded pulp bottle. It is easily applied, easily crimped, and forms a leak-proof seal. Furthermore, there are no raw edges which cut into the pulp wall, but, 50 rather, a rounded finished rib portion results which strengthens the neck and cap structure. The cap is easily removed, but, simultaneously with the removal, the bottle is rendered impractical for further use.

55 While certain novel features of the invention have been disclosed and are pointed out in the annexed claims, it will be understood that various omissions, substitutions and changes may be made by those skilled in the art without 60 departing from the spirit of the invention.

What is claimed is:

1. The combination with a bottle formed from molded pulp fibres and having a wall defining a

reduced neck surrounding an open mouth, of a one piece, thin metal cap comprising a cup portion having a cylindrical side wall lying against the inner face of said bottle wall, a rim overlying the edge of said bottle wall, an apron depending from said rim and overlying the outer face of said bottle wall, and a bead rolled outwardly and against the outer face of said apron, said apron being curved inwardly substantially throughout its height to indent the adjacent portion of said bottle wall and lock said cap on said bottle to thereby prevent removal of the cap except upon mutilation of said bottle, said apron being curved inwardly sufficiently to prevent said bead from projecting laterally beyond said rim but on a sufficiently long radius to prevent any substantial weakening of the bottle wall.

2. The combination with a bottle formed from molded pulp fibres and having a wall defining a reduced neck surrounding an open mouth, of a one piece, thin metal cap comprising a cup portion having a cylindrical side wall lying against the inner face of said bottle wall, a rim overlying the edge of said bottle wall, an apron depending from said rim and overlying the outer face of said bottle wall, and the edge of said apron being rolled outwardly and back against the outer face of said apron to provide a bead, said bead being of such diameter that said apron is curved inwardly substantially throughout its height to 2 indent the adjacent portion of said bottle wall and lock said cap on said bottle to thereby prevent removal of the cap except upon mutilation of said bottle, said apron being curved inwardly 3 sufficiently to prevent said bead from projecting laterally beyond said rim but on a sufficiently long radius to prevent any substantial weakening of the bottle wall.

3. The combination with a bottle formed from molded pulp fibres and having a wall defining a reduced neck surrounding an open mouth, of a one piece, thin metal cap comprising a cup portion having a cylindrical side wall lying against the inner face of said bottle wall, a rim overlying the edge of said bottle wall, an apron depending from said rim and overlying the outer face of said bottle wall, and a bead rolled outwardly and against the outer face of said apron, said apron being curved inwardly through its height to indent the adjacent portion of said bottle wall and lock said cap on said bottle to thereby prevent removal of the cap except upon mutilation of said bottle, said apron being curved inwardly sufficiently to prevent said bead from projecting laterally beyond said rim but on a sufficiently long radius to prevent any substantial weakening of the bottle wall, said bottle having spaced horizontal ribs below the lower end of the cap, said cap extending a sufficient distance into the bottle and said ribs being sufficiently spaced to cause 50 said bottle to tear at the portion lying between the ribs when said cap is removed.

ROY D. HEYMANN.
